CARBURATION DEVICE

Harry W. Hess, Milwaukee, Wis., assignor to
 Carburetor Control Company, a corporation of
 Nevada

Application August 12, 1929. Serial No. 385,269

8 Claims. (Cl. 261—51)

This invention relates in general to the carburation or vaporization and conditioning of fuel for combustion thereof for energy producing purposes, and the invention finds particularly useful application in connection with the admission of a supply of properly mixed liquid fuel and air to the cylinders or manifold of an internal combustion engine, although the utility of features of the invention is of more general scope and application; but, for purposes of presenting the invention, the disclosure will be more particularly directed to the application of the invention for use with an internal combustion engine of the liquid fuel type, such as is ordinarily used on automobiles.

Control of an internal combustion engine is secured through regulation of the supply of hydro-carbon fuel and air which produce the fuel mixture fed to the cylinders. Inefficiency of operation and reduced power in the operation of an internal combustion engine are incidents of over-rich or over-lean mixtures of fuel and air supplied to the engine cylinders; and the supply of an over-rich mixture has the further defect of causing excessive carbon deposits in the engine cylinders during operation. In order to insure efficient operation and desired uniformity of power response and regularity of acceleration, it is ordinarily desirable that, for the various positions of the throttle, or valve device regulating the admission of fuel mixture to the engine, the proportions of fuel and air should be constant throughout the entire range of engine speed, or from idling condition to full-open throttle condition.

A general object and purpose of the present invention is the provision of an improved form of carbureting device capable of readily insuring uniformity to the desired degree in the matter of the proportions of air and vaporized hydro-carbon fuel in the combustible mixture, throughout the full range of control, to the end of attaining smooth operation throughout the entire speed range, with fast acceleration and high maximum power, along with a high degree of general efficiency and economy in the operation of an internal combustion engine with which the carburetor is associated.

The present invention contemplates as a particularly desirable feature thereof the provision of a carburetor for preparing and feeding to an internal combustion engine or the like a mixture of air and vaporized fuel, wherein the supply of fuel is definitely regulated with respect to the particular operating speed or power de-

sired, as may be determined by the position of a throttle, and is coupled with the supply in an automatically controlled manner of just the desired amount of air to produce with the fuel supplied a fuel mixture composed of desirably uniform proportions of air and fuel, to thus insure efficient operation of the engine. And, in accordance with certain features of the invention, the control of the supply of liquid fuel is secured through utilization of an improved form of fuel-controlling valve affording fine regulation and metering of the fuel and rendering the degree of opening of such valve definitely proportional to the degree of opening of the throttle. And a further feature of the invention includes the utilization of an air admission controlling valve whose operation is automatically responsive to the suction drag or degree of depression present in the engine cylinders, or manifold associated therewith, as determined by the position of the throttle, the design and arrangement of parts of this air controlling valve being such as to insure a readily controlled automatic operation of the valve with an immediate and delicate response, from its minimum-open to its maximum-open position, with consequent maximum available power and maximum economy in the matter of fuel consumption.

Various additional features and objects of this invention, concerned with the controlled supply of air and fuel to the carburetor and of the combined or mixed air and fuel to the engine, and structural arrangements and mechanical details concerned therewith, will be apparent from the more detailed description of the invention contained in the specification hereinafter and from the accompanying drawing disclosing embodiments of the invention, and will be more particularly pointed out in the claims.

In the drawing:

Fig. 1 is a broken sectional elevation of a carburetor embodying features of the present invention, the plane of the section being that of the line I—I of Fig. 2.

Fig. 2 is a view similar to Fig. 1, the plane of section being that of the line II—II of Fig. 1.

Fig. 3 is a broken sectional elevation of the device as shown in Fig. 2, the section being in the plane of the line III—III of Fig. 1.

Fig. 4 is a bottom plan view of the device shown in Fig. 2.

Fig. 5 is a view similar to Fig. 3, with parts broken away, and embodying modifications of certain features.

In accordance with the disclosure of the draw-

ing, 5 indicates a fuel float chamber such as is customarily associated with carburetors for use with internal combustion engines of automobiles; and 6 indicates the body portion, of rectangular cross-section, of a riser element or chamber into which the fuel and gas are admitted and wherein they are mixed prior to the supply of the mixture to the engine cylinders. The float chamber and riser chamber are preferably, as indicated, 10 formed separately but are so designed as to be readily assembled as a unit and detachable from one another when necessary. The float chamber is provided with an enlarged hollow extension 7 at one side thereof forming a portion of or 15 having its interior communicating with the main fuel chamber 5, and this extension 7 is provided with spaced projections 8 and 9 extending at substantially right angles from a portion or pad 10 formed on a side wall of the extension 7. 20 The projection or extension 8 is provided with a bore 11 communicating, as will be described hereinafter, with the interior of the extension 7 of the float chamber; and there is provided at the upper side of the extension 8 at a medial point 25 thereof, an aperture communicating with the bore 11 and in which is mounted, preferably in a detachable manner, a fuel supply nipple 12 having a nozzle portion 13 of suitable known design at its upper end and projecting axially into a central aperture 14 through the bar-like upper 30 projection 9. The diameter of the nipple is such that it can be inserted to and from operative position through the aperture 14, and the nozzle portion 13 is sufficiently reduced as to leave an annular space of ample size between the outer 35 wall of the nipple and the wall of the aperture 14 to permit the passage therethrough of a supply of air to satisfactorily take care of idling conditions of the engine, the walls of the aperture 14 projecting to a substantial extent above the nipple, thus confining the air passing through the aperture 14 in such a manner as to insure its ready contact and commingling with the fuel drawn through the nozzle 13, during operation of 40 the assembled carburetor.

The bar-like projections 8 and 9 preferably project from the extension 7 of the float chamber to such a point that when the wall of the riser chamber 6 is held against the face of the 45 pad 10, with these projections 8 and 9 extending through an aperture formed in such side wall, the outer end of each of the projections 8 and 9 is in close proximity to or abuts against the inner face of the opposite wall of the riser chamber. The 50 float chamber 5 and the riser chamber 6 are shown assembled in operative position, with the axis of the aperture 14 and the fuel nozzle 13 in alignment with the axis of the riser chamber, and with the projections 8 and 9 extending 55 through an aperture, with a relatively close fit therein, in the corresponding side wall of the riser chamber, adjacent parts of this side wall abutting flatwise against the face of the pad 10 on the extension 7 of the float chamber. A raised 60 portion may be formed on the outer face of the pad 10 to enter and fill that portion of the aperture in the adjacent side wall of the riser chamber unoccupied by the projections 8 and 9. Extensions or lugs 16 are preferably formed at the 65 side edges of the pad 10 and embrace the side walls of the riser chamber to hold the latter against lateral shifting. With the float and riser chamber thus assembled, these parts are held in fixed position preferably by screws 17 passing 70 through a clamping plate 18, held against the 75

opposite side wall of the riser chamber, and through the latter side wall, these screws 17 being threaded into apertures in the adjacent ends of the spaced projections 8 and 9. The clamping plate 18 may be provided at its side edges with 80 projections or lugs 19 which engage the faces of the adjacent side walls of the riser chamber and assist in holding the parts against lateral displacement. With the clamping screws 17 drawn up to position, the riser chamber is 85 securely clamped in operative position relative to the float chamber 5 and its appurtenant fuel-feeding parts in such a manner as to insure the passage of fuel from the float chamber and to and through the fuel discharge nozzle 13. 90

Fuel is fed from the float chamber 5, a regulating valve 20 controlling the passage of fuel from the hollow extension 7 of the float chamber. This regulating valve comprises a fixed seating element 21 of tubular formation having a 95 slightly flared or conical seating face on its interior, with the larger diameter of the flared seat at the upper end thereof, where it opens to the fuel in the extension chamber 7, and tapering, in diameter, preferably with a straight taper, toward its lower end. A movable valve element 23 of the needle type, and preferably straight sided or cylindrical throughout its active controlling portion, is arranged to be reciprocated within and to cooperate with the tapered seating face or 100 bore of the seating element 21, to meter or control the passage of fuel through the valve. As indicated, the seating element 21 is preferably made up in the form of a bushing threaded adjacent its upper end into an aperture formed in 105 the lower wall of the extension 7 of the float chamber.

The quantity of fuel that may pass through the valve is determined by the degree to which the needle is displaced upwardly from its lowermost position wherein the lower end of the needle is in engagement, or substantial engagement, along an annular surface or a line, with the adjacent portion of the interior seat 21. By shifting the position of the needle 23 upwards or 110 downwards within its flared seat 21, an annular opening of variable size is formed between the lower end of the needle and the portion of the flared seat adjacent thereto, a feature which permits extremely fine metering or regulation of the 115 amount of fuel discharged downwardly through the valve. Through the presence of a gradual contraction up to the metering throat between the end of the needle 23 and its seat 21, the same being located at a relatively low point in the 120 assembly where it is subjected to considerable head, fuel is discharged through the contracted annular metering passage with sufficiently high velocity to keep even a fine opening clear. Fuel discharges from the valve 20 into a chamber or 125 supply well 24, preferably formed by a detachable cap or thimble 24 threaded into the wall of a bore or apertured portion at the lower side wall of the extension 7 of the float chamber. Communication is established between the supply well 24 and the bore or passage 11 in the 130 projection 8 communicating with the nozzle 13, through a passage or bore 25 formed through the lower wall of the extension 7 of the float chamber. 135

Air enters the carburetor through the lower end of the riser chamber 6 of rectangular cross-section, this lower end of the latter, in the form shown herein, being cut away at an angle of approximately 45 degrees so as to facilitate the en- 140

trance of the air from a lateral direction. The supply of air through the lower portion of the riser chamber and into the upper portion thereof or mixing chamber, indicated at 36, is controlled by means of a special type of valve which is automatically responsive in its operation to the adjustment of the throttle control and the suction drag or depression of the engine cylinders incident thereto. This air controlling valve is shown in the form of a pair of opposed, similarly shaped and symmetrically arranged resilient leaves 28, 29, having their lower ends secured in position adjacent opposite side walls, as by pivotally mounting these lower ends on pins so as to permit oscillation thereon, as indicated at 30. These resilient leaves are of such shape, under normal or unbiased conditions, and are so dimensioned and disposed in the riser chamber that their intermediate portions are biased to bear lightly against the side walls of the projection or cross bar 9 which surrounds the discharge end of the nozzle 13, as indicated in full lines in Fig. 3. The upper ends of these resilient leaves 28, 29 bear against the inner faces of the adjacent side walls of the mixing chamber 36, being slightly rounded at these ends, as indicated at 32, to facilitate sliding movement of the ends along the wall of the chamber. Pins 34 pass through opposed side walls of the chamber and serve to retain the upper ends of the springs against appreciable displacement away from the side walls with which they engage, while still permitting their displacement longitudinally along these side walls as the intermediate portions of the leaves flatten out during operation of the carburetor.

It is desirable that the intermediate portion of the resilient leaves 28, 29 where they approach one another most closely be adjacent, preferably slightly above, the discharge end of the nozzle 23, for the air passing through this throat or contracted portion, indicated at 31, of the venturi formed by the leaves and the side walls is at maximum velocity and exerts a beneficial drag on the fuel supplied through the nozzle and imparts a desirable breaking-up effect on the particles of fuel discharged from the nozzle.

The portions of the resilient leaves 28, 29 below the cross bar 9, corresponding to the point of greatest contraction 31 of the passage between the inwardly bulged portions of the opposed resilient leaves, are of full width, i. e., they extend across the full width of the passage through the riser chamber and their edges cooperate with opposed straight sided walls of this chamber, preferably with a minimum clearance, so as to permit the desired movement of the spring transversely thereof while at the same time preventing leakage of pressure air to the rear side of the leaves.

The portions of the resilient leaves 28, 29 above the extension cross bar 9 are recessed or cut away to permit the rear sides of these leaves throughout their full length to be exposed to any depression or vacuum existing in the mixing chamber, due to the suction drag of the engine cylinders. To secure this effect each of the resilient leaves 28, 29 may be cut away, as indicated, at its side edges, from a point appreciably above the inwardly bulged intermediate part of the spring which is biased against the cross bar 9. Further, through this gradual reduction of the width of the leaves at their upper ends, these portions of the leaves have decreased inertia and are more flexible, and hence more readily displaceable or distortable from normal biased

condition during operation of the carburetor. By having the upper ends of the resilient leaves 28, 29 bearing against the walls of the chamber, tendency to uncontrolled vibration of the leaves and pulsation during operation is minimized.

Through the arrangement of the parts of the air valve, all of air admitted to the mixing chamber is metered or controlled, by reason of its passage through the throat 31 of the Venturi tube of automatically variable cross-section formed between the inwardly bulged or contracted portions of the resilient leaves 28, 29, the edges of the lower portions of the latter cooperating with the opposed side walls of the chamber so that there is no appreciable leakage of air between the edges of the leaves and the side walls of the chamber at the inlet side of the contracted throat, such as might cause undesirable variations in the proportion of air and fuel admitted to the mixing chamber. With this arrangement, the lower portions of the resilient leaves below the contracted throat 31 have their front faces exposed to the air pressure at the inlet side of the valve, and the rear faces of these lower portions of the leaves are exposed to only the suction or depression existing in the mixing chamber. And this fluid pressure differential exerted on the resilient leaves, the same being balanced by the elasticity of the leaves as they are distorted to a variable degree toward flattened condition, depending upon the speed of operation of the engine, is a material factor in avoiding sluggishness in the opening and closing movements of the air controlling valve and in insuring the desired ready and delicate responsiveness of this air valve in automatically providing the required flow of air to the mixing chamber and the desired uniformity of proportions of air and fuel.

Fuel drawn in vapor form into the mixing chamber 36 from the nozzle 13 is surrounded by and quite thoroughly mixed with air drawn through the opening 14 in the cross bar 9 and between the walls of Venturi throat 31 of variable size formed between the inwardly bulged intermediate portions of the resilient leaves 28, 29 which, as they are distorted more or less from their normal biased positions during operation of the engine, have the effect of varying the cross-sectional area of this mixing chamber at its lower portion.

The mixture of air and vaporized fuel is fed from the mixing chamber 36 to the engine cylinders, or the manifold associated therewith, through a controlling throttle valve 41 of the butterfly type, indicated as being of rectangular outline for cooperation with and closure of the passage of rectangular cross-section through the upper portion of the riser chamber 6. This throttle valve is mounted on a spindle 42 passing through the side walls of the riser, and it is preferably mounted in depending extensions of an enlarged cap portion 43 fixed to the upper end of the riser. The throttle may be operated, through its spindle 42 and an actuating rod connected to a crank arm 45 fixedly mounted upon the spindle, by a handle or treadle disposed in any position convenient to an operator. A stop, here shown in the form of a screw 46 adjustable in a projection 47 on the crank 45, may cooperate with a fixed stop or projection 48 of the casting 43, to variably determine the closed, or nearly closed, position of the throttle, corresponding to desired idling conditions of the engine. This cap portion 43 is preferably in the form of a separate casting, particularly where the riser

chamber can be formed of stock shapes and sizes and the machine work necessary to constitute a suitable mounting for the throttle valve and parts, may be done on the part 43 before the latter is attached to the riser.

While certain features of the present invention may be realized with a carburetor wherein there is a single fixed or manually controllable opening for supply of fuel to the carburetor, some variation in the amount of fuel supplied being afforded by differences in suction drag exerted by the engine due to variations in speed of the latter, nevertheless, the most desirable operating characteristics are attained in a carburetor of the general type described above wherein the supply of fuel to the carburetor is made to correspond more definitely and assuredly to the requirements of the engine in the matter of speed and power. Accordingly, the movable needle element 23 of the fuel regulating valve is caused to be actuated to a position to produce an opening through the valve 20 which always bears a desired definite relation to the position of the throttle valve, and hence, to the required speed and power of the engine.

As indicated, the needle valve 23 is fixedly attached to a rod 51, as by having the upper end of the needle valve fitting within a socket at the lower end of the rod 51 and having flexible side walls which, after the needle is inserted into position in the socket, may be clamped and held in position about the needle by means of a clamping nut 52 threaded upon the flexible side walls of the socketed portion of the rod. This rod 51 preferably passes out of the chamber formed in the extension 7 of the float chamber, through an apertured cap or bushing 53 secured, as by threading, in an opening formed in the upper wall of the extension 7 of the float chamber. This opening in which the bushing 53 is detachably secured, is of sufficient size to permit the ready removal and replacement therethrough of the tubular seating element 21 of the fuel regulating valve 20 which is formed at its upper end for engagement with a suitable tool. A compression spring 54 surrounds the rod 51, bearing at its upper end against the under side of the cap portion of the bushing 53, and at its lower end against the clamping nut 52 at the lower end of the rod 51; and this spring serves to bias the needle valve downwardly toward closed or desired idling position, insuring its automatic return to lower position whenever the needle is relieved of operating pressure.

As indicated, the throttle valve 41 is connected to the operating rod 51 of the needle 23 of the fuel metering valve, for one-way positive operation of the latter, through a link 55 flexibly connected to the upper end of the rod 51 and to a crank 56 loose upon the spindle 42 of the throttle and provided with an off-set lug or extension 58; and an adjustable stop 59 threaded through a projection 60 on a crank arm 61 fixed to the spindle 42 bears against the upper side of the projection 58. With this arrangement, operation of the throttle 41 toward full-open position, that is, in a clockwise direction, as viewed in Fig. 2, causes the opening of the needle 23, through the action of the stop 59 bearing upon the projection 58 on the loose crank 56 to which the connecting link 55 is attached. This operating connection is such that as the throttle is opened, the needle valve 23 is opened to a corresponding desired amount, definitely determined by the lever arm of the crank 56 and the degree of taper of the

valve seat 21; and then, as the throttle is released or closed, the needle 23 of the fuel metering valve is immediately forced, through the action of the biasing spring 54, to a closed or partly closed position, corresponding to the new position 80 of the throttle, at which time the projection 58 on the loose crank 56 abuts against the adjustable stop 59 associated with the operating parts of the throttle.

The initial or idle position of the fuel metering 85 valve, and the amount of fuel supplied for a particular throttle opening may be adjusted at will by adjusting the position of the stop 59 against which the projecting lug 58 on the crank 56 abuts, this adjustment, coupled with the effect of the 90 biasing spring 54, serving to raise or lower the needle 23 relative to its seat 21 to thereby vary the opening through the valve. Further adjustment of the fuel metering valve may be accomplished by replacing the needle 23 with another of 95 different diameter which, for a given needle position, affords a correspondingly larger or smaller passage between the lower end of the needle and the seat 21.

In order to provide for opening of the fuel 100 metering valve 20 independently of the throttle and its adjustment relative to the fuel valve, such as may be necessary for cold-weather starting, a crank 63 is mounted loosely on the spindle 42 of the throttle and is provided with a projecting 105 nose 63a which, on suitable actuation of this crank in a clockwise direction, as by means of a connecting rod passing to the operator's position, engages with the outer end of the extension 58 on the crank 56, shifting the latter in a clockwise 110 direction and thereby lifting the needle 23 of the fuel valve away from its tubular seat to the desired degree. On relieving the crank 63 of operating pressure, the biasing spring 54 immediately shifts the needle valve to a closed or other position, corresponding to the position of the throttle 115 at the time.

An auxiliary supply or by-pass for the feeding of fuel from the float chamber 5 to the fuel nozzle 120 13 may be provided through a port 64 in the lower 120 side wall of the hollow extension 7, this port communicating with the well 24. A needle valve 65 cooperates with this port for varying the size thereof or closing the port, a portion of this valve passing through the upper wall of the hollow 125 chamber 7 and formed at its upper end to permit adjustment from the outside of the casing of the degree of opening of the valve. Or, this valve 65 may have its upper end formed for connection to a loose crank such as 63 for adjustment thereby, through an operating connection, from the operator's position.

Assume that the engine has been started and is operating under idling conditions, the throttle being opened or "cracked" slightly, as determined 130 by the adjustment of the stop screw 46, and with the fuel metering valve open to its predetermined idling or nearly closed position, and the air valve with the inwardly bulged intermediate portions against the sides of the cross bar 9, as 140 indicated in full lines in Fig. 3. Under these conditions, a minimum amount of fuel is fed to the nozzle 13 whence it is drawn, along with the proper amount of air passing through the opening 14 in the cross bar 9, into the mixing chamber 145 36, and the mixture is drawn therefrom through the throttle to the manifold or engine cylinders. Through proper design and proportioning of the air and fuel valves, in general accordance with 150 the disclosure hereinabove, a minimum amount of

fuel is fed under these conditions, just enough to maintain the engine in operation with no load thereon.

In order to bring the engine up to any desired operating speed, the throttle is actuated to a position corresponding to the desired speed, and the fuel metering valve, through the operating connection therebetween and the throttle during its opening adjustment, is also opened to a degree corresponding to the particular setting of the throttle. The suction of the engine cylinders is immediately effective to draw an increased amount of fuel through the supply nozzle 13 and, likewise, the increased suction drag, due to the opening of the throttle, is immediately effective to cause an increased supply of air through the air valve, the leaves 28, 29 of the air valve moving outwardly toward their flattened position, due to the differential pressure exerted thereon by the incoming air passing through the throttle of the venturi formed by the intermediate bulged portions of the resilient leaves. These leaves are distorted or flattened to a position determined by the design of the leaves and the particular setting of the throttle, the result being that the opening between these leaves is just sufficient to supply under the suction drag conditions incident to the particular degree of opening of the throttle, just the required amount of air for mixture with the supply of fuel passing through the fuel metering valve whose position is likewise determined by the position of the throttle.

In the modification shown in Fig. 5, the riser chamber 6^a is indicated as being of special shape particularly designed to provide space for receiving the opposed leaves 28^a, 29^a constituting the air valve when the latter is in maximum open position, to the end that, when this valve is in maximum open position, there will be a through passage between the opposed leaves which is substantially equal in cross-sectional area to the inlet portion of the riser chamber. As indicated, opposed side walls of the riser chamber are distorted outwardly adjacent the leaves, from the pivotal point to the upper end thereof, thus providing recesses which receive the spring in its maximum open position, indicated in dotted lines.

While the inherent resilience of the leaves 28 and 29 themselves, constituting the automatic air valve, is relied on wholly in the particular embodiments of the invention described herein, to insure the proper opening of the air valve at all times, certain desirable results are attainable with valve leaves in connection with which separate springs are utilized in whole or in part to bias and return the leaves to minimum open position.

It is an interesting feature of the operation of the present carburetor that the response in the matter of an increased or decreased supply of air, corresponding to any opening or closing adjustment of the throttle is immediate, for the operation of the throttle varies to pressure to which the rear sides of the resilient leaves are exposed, thus distorting or destroying the normal equilibrium or balance existing for the theretofore existing throttle adjustment. Through the above described several features of design, the highly desirable result is attained that a uniform proportion of air and fuel is supplied to the engine from the minimum opening or idling position of the throttle and associated parts to the maximum opening thereof, corresponding to maximum speed of operation of the engine. And further, through this design and arrange-

ment of parts, the depression or suction available in the mixing chamber or at the discharge side of the air valve varies at a uniform rate from idling or minimum open position of the throttle, corresponding to minimum operating speed, to maximum opening, or maximum speed condition of the engine, the general result being that maximum power and maximum economy of fuel is available under all operating conditions of the engine.

While the riser chamber 6 is shown as being of rectangular cross-section throughout, any portion of the same above the active controlling portion of the leaves 28, 29 of the air valve may, with reasonably satisfactory results, be of a section other than rectangular. However, with a butterfly valve of rectangular outline cooperating with a correspondingly shaped casing, the open area or passage through the latter more readily provides a passage of uniformly varying area as the throttle is opened. Likewise, the rectangular form of throttle cooperates better with a simple design of fuel metering valve of relatively straight taper, to secure the desired uniformity of proportions of fuel and air, as the throttle is opened.

It should be understood that the invention claimed is not limited to the details of construction and operation described hereinabove, for obvious modifications within the scope of the appended claims will occur to those skilled in the art and are to be considered as included within the general scope of the invention.

It is claimed and desired to secure by Letters Patent:

1. In a carburation device, the combination of a fuel mixing chamber, means for automatically controlling the admission of air to said mixing chamber, said means comprising a leaf valve having an intermediate portion resiliently urged toward a position to close the through passage of air and movable transversely across a portion of the casing element having opposed parallel side walls with which the edge portions of said leaf valve cooperate to prevent the passage of air from the inlet side thereof between said edges and said walls of the valve chamber, while permitting free exposure of the rear side of said leaf valve to the pressure conditions present in said mixing chamber.

2. In a carburation device, the combination of a fuel mixing chamber, of an automatically operated valve for controlling the admission of air to said mixing chamber, said valve being resiliently biased to closed position and being movable to open position in response to the suction available in said mixing chamber, said valve including a plurality of symmetrically disposed and opposed leaves providing a Venturi throttle of variable throat opening, and a casing element therefor having opposed parallel side walls with which the edge portions of said leaves cooperate in a substantially fluid tight manner during movement of said leaves from their closed position

wherein they approach each other to a maximum extent, whereby the inlet sides of each of said leaves is open to the pressure of incoming air whereas the rear side of said leaves is freely exposed to the suction available in said mixing

chamber.

3. In a carburation device, the combination of a casing having therein, a fuel supply chamber, a fuel mixing chamber, and means for controlling the supply of fuel from said supply chamber to

150

said mixing chamber, said means comprising a nozzle disposed adjacent said mixing chamber, and a fuel controlling valve controlling the passage of fuel from said supply chamber, said valve 5 including a seat member of tubular formation having a flared internal seat, mounted in the lower wall of said fuel supply chamber, a movable controlling needle disposed within said tubular seat having its end portion of a cross-sectional 10 area at least equal to that of the shank portion of said needle, said end portion constituting the effective valve element for varying the size of the effective passage therethrough between said seat and the end of said needle.

15 4. In a carburation device, the combination of a fuel supply chamber, a fuel mixing chamber, and means for controlling the supply of fuel from said supply chamber to said mixing chamber, said means comprising a nozzle disposed adjacent said mixing chamber, and a fuel controlling valve controlling the passage of fuel from said supply chamber, said valve including a seat member of tubular formation having a flared internal seat, a movable controlling needle disposed within said tubular 20 inlet having its end portion of a cross-sectional area at least equal to that of the shank portion of said needle, said end portion constituting the effective valve element for varying the size of the effective passage therethrough between said seat and the end of said needle, a throttle for controlling the fuel mixture discharged from said mixing chamber, and a mechanical connection between said throttle and said fuel supply valve for insuring the opening of said fuel supply valve 25 to a degree proportionate to the opening of said throttle.

5. In a carburetor, the combination of a fuel mixing chamber, means for controlling the admission of air to said mixing chamber, said latter 40 means comprising a plurality of leaves uniformly distributed about the axis of said mixing chamber and cooperative with wall portions at the inlet side of said mixing chamber to produce a Venturi throttle of variable throat opening, the rear faces 45 of said leaves being exposed to only the pressure in the mixing chamber at the discharge side of said air valve, and a fuel supply nozzle having its discharge opening between said leaves adjacent the point of greatest constriction therebetween.

50 6. In a carburetor, the combination of a fuel mixing chamber, an automatically operable valve for controlling the admission of air to said mixing chamber, said valve comprising a plurality of leaves symmetrically disposed about the axis of 55

said mixing chamber and forming a variable venturi therein and yielding biased toward each other to decrease the size of the Venturi passage formed therebetween, said leaves cooperating with the walls of said chamber to close the rear faces of said leaves to pressure other than that existing in the mixing chamber beyond the throat of said venturi, an element extending across said chamber and serving as a stop to limit the movement of said valve members toward each other, said stop being apertured in substantial alinement with the axis of said mixing chamber, and a fuel discharge nozzle extending into the aperture in said stop and spaced from the walls thereof, to insure an air passage about the discharge end of said nozzle when said leaves are in position to provide minimum opening therebetween. 80 85 90 95

7. In a carburetor, the combination of a mixing chamber, a throttle valve of rectangular outline cooperating with the walls of a passage of rectangular cross-section for controlling the discharge from said mixing chamber, and a reciprocating valve for controlling the supply of fuel to said mixing chamber, said fuel valve being associated with said throttle for actuation in synchronism therewith and being biased toward closed position independently of said throttle, the operating connection between said throttle and said fuel valve insuring the positive actuation of said fuel valve to open position and the automatic return of said fuel valve following closing movement of said throttle. 100 105 110

8. In a carburetor, a two-part casing structure, one part of said casing including a fuel supply chamber, a fuel discharge nozzle, and a valve for controlling communication between said fuel supply chamber and said fuel nozzle, and a second part of said casing including a mixing chamber, a throttle valve for controlling the discharge from said mixing chamber, and an air admission controlling valve comprising a plurality of separable leaves biased toward each other for controlling the admission of air to said mixing chamber, and means for securing the two parts of said casing in operative position relative to each other, with said fuel discharge nozzle disposed in substantial alinement with the axis of said mixing chamber and located at the point of minimum opening between the leaves of said air controlling valve, said fuel controlling valve being connected to said throttle valve for synchronous opening movement therewith. 115 120 125 130 135
